United States Patent Office

Des. 215,784
Patented Oct. 28, 1969

215,784

TEXTILE FABRIC

Stanley Ball, Rockaway Beach, N.Y., assignor to Cannon
Mills Company, Kannapolis, N.C., a corporation of North Carolina

Filed Nov. 25, 1968, Ser. No. 14,654

Term of patent 14 years

Int. Cl. D5—02

U.S. Cl. D92—1

Fig-1

FIGURE 2 is an enlarged top plan view of one repeat of the design and corresponding substantially to that area enclosed within the dotted lines of FIGURE 1.

I claim:

The ornamental design for a textile fabric, substantially as shown and described.
